[57] CLAIM

The ornamental design for a bag pack, as shown and described.

DESCRIPTION

FIG. 1 is a perspective view of a bag pack showing my new design, the opposite side being the same in appearance;

FIG. 2 is a perspective view of one of the bags comprising the bag pack, the opposite side being the same in appearance;

FIG. 3 is a perspective view of the bag of FIG. 2 as pulled from the bag pack with the two opposed tab portions torn away;

FIG. 4 is a perspective view with the bag expanded for use;

FIG. 5 is a side elevational view thereof; and

FIG. 6 is a top sectional view taken through the center of FIG. 5.

FIG. 2
